UNITED STATES PATENT OFFICE.

BOYDEN KINSEY, OF WYOMING, OHIO

CONCRETE VAULT.

No. 875,639.

Specification of Letters Patent. Patented Feb. 11, 1908.

Application filed July 26, 1907. Serial No. 385,655.

To all whom it may concern:

Be it known that I, BOYDEN KINSEY, a citizen of the United States of America, and resident of Wyoming, county of Hamilton, 5 State of Ohio, have invented certain new and useful Improvements in Concrete Vaults, of which the following is a specification.

The object of my invention is a vault or safe which is both fire and burglar proof. I 10 attain this object by making the walls of a construction such that they cannot be penetrated by a tool to a sufficient depth for the insertion of explosives in the vault, and, likewise, by an arrangement of the reinforcing 15 bars such that they do not interfere with the monolithic character of the walls.

In the accompanying drawings, Figure 1 is a horizontal sectional view of a vault embodying my invention. Fig. 2 is a sectional view 20 of one of the tool proof bars used in the walls, the view being taken upon a somewhat enlarged scale, showing its action upon the point of the drill which should strike in the direction otherwise than at a right angle to 25 its surface.

The invention has been illustrated in a vault whose walls would be approximately fifteen inches in thickness. Within the concrete, A, near the inner surfaces, a, of the 30 walls is placed a steel webbing made up of a series of equally spaced cold twisted steel bars, B, in horizontal planes and the same character of steel bars, C, placed vertically. About four or five inches from the outer 35 faces, a', of the concrete, I have arranged a series of tool proof steel bars, D, at acute angles to the outer faces, a', of the walls. The bars, D, in a wall are arranged preferably in parallel planes so that the vertical plane cutting the end of one bar at right angles to the outer faces, a', would cut also the end of an adjacent bar. Bars, D, are made preferably 40 from five ply or chrome steel, that is, two of the plies d, of this bar would be tool proof 45 steel and the central and outer plies, d', of a softer steel. As is recognized in the art the hardened steel resists to a greater extent the passage of a tool, while the softer steel prevents the bar from being fractured by a blow.

50 A space is left between the last bar of a wall and the first bar of the intersecting wall, so that there is enough room between these bars at the corner for the concrete. Beyond these adjacent bars in the corners a chrome

steel bar, D', is placed at an angle acute to 55 the outer meeting faces of the walls. The concrete used in vaults of this character is very hard and difficult to drill.

Should one attempt to penetrate a wall in which the bars were arranged at an acute 60 angle to the outer face of the wall, and should not start with his drill, E, at exactly a right angle to the faces of the bars, the point, e, thereof would be turned when it met the tool proof steel, d, since it would 65 strike the same at an acute angle. The chances of starting the tool in at right angles to the face of the bars where the angle is not known, are limited. The chances, likewise, 70 of passing a drill between the bars are likewise limited and in this instance, the great distance to be bored to pass through the wall between bars in view of the difficulty of drilling this hardened concrete would render the task one very difficult to perform, since 75 the farther the point of the drill is from its shank, the greater becomes the danger of breaking it.

The bars being spaced at distances apart and arranged with their angles overlapping 80 each other attains the object of limiting the chances of passing a tool through the wall after striking a bar, while at the same time it allows a proper space between the bars for the occupation of the concrete, so that the 85 concrete will have a monolithic character, which will prevent its being split into cracks.

What I claim is:

1. A concrete vault having arranged within its walls a series of tool proof bars set at acute angles to the outer faces of the concrete walls.
2. In a concrete vault the combination of concrete walls with a series of tool proof bars within each wall placed parallel to each other at a slight distance apart and at an acute angle to the outer faces of the concrete.
3. In a vault the combination of a concrete wall, with a series of tool proof bars located therein and arranged at acute angles to its outer face and set at such a distance apart that planes perpendicular to the outer face of the wall would cut the ends of the adjacent bars.

BOYDEN KINSEY.
